(57) CLAIM

The ornamental design for a fitting for an endoscope device having protuberances, as shown and described.

DESCRIPTION

FIG. 1 is a perspective view of a fitting for an endoscope device having protuberances;

FIG. 2 is a front view of the fitting for an endoscope device having protuberances, the back view being identical thereto; FIG. 3 is a left view of the fitting for an endoscope device having protuberances, the right view being identical thereto; FIG. 4 is a top view of the fitting for an endoscope device having protuberances;

FIG. 5 is a bottom view of the fitting for an endoscope device having protuberances;

FIG. 6 is a perspective view of the fitting for an endoscope device having protuberances;

FIG. 7 is a front view of the fitting for an endoscope device having protuberances, the back view being identical thereto; FIG. 8 is a left view of the fitting for an endoscope device having protuberances, the right view being identical thereto; FIG. 9 is a top view of the fitting for an endoscope device having protuberances;

FIG. 10 is a bottom view of the fitting for an endoscope device having protuberances;

FIG. 11 is a perspective view of the fitting for an endoscope device having protuberances;

FIG. 12 is a front view of the fitting for an endoscope device having protuberances, the back, left and right views being identical thereto;

FIG. 13 is a top view of the fitting for an endoscope device having protuberances; and,

FIG. 14 is a bottom view of the fitting for an endoscope device having protuberances.

The broken lines of the figures depict unclaimed portions of the fitting for an endoscope device having protuberances only and form no part of the claimed design.

1 Claim, 14 Drawing Sheets
